<div data-bbox=)

(57) **CLAIM**

The ornamental design for a contact lens applicator as shown and described.

DESCRIPTION

- 1.1** : Perspective
1.2 : Perspective
1.3 : Front
1.4 : Back
1.5 : Left

(Continued)

1.6 : Right

1.7 : Top

1.8 : Bottom

1.9 : Reference

The broken lines illustrate environmental subject matter that form no part of the claimed design.

1 Claim, 8 Drawing Sheets
